UNITED STATES PATENT OFFICE.

ADAM A. E. SNYDER, OF BANGOR, PENNSYLVANIA.

ADJUSTABLE OVERHEAD SUPPORT FOR HOISTS.

1,309,048.

Specification of Letters Patent.

Patented July 8, 1919.

Application filed November 21, 1918. Serial No. 263,541.

To all whom it may concern:

Be it known that I, ADAM A. E. SNYDER, a citizen of the United States, residing at Bangor, in the county of Northampton, 5 State of Pennsylvania, have invented a new and useful Adjustable Overhead Support for Hoists; and I do hereby declare the following to be a full, clear, and exact description of the invention, such as will enable 10 others skilled in the art to which it appertains to make and use the same.

The present invention relates to an overhead support for hoists and the like, and has for its object to provide a device of this 15 character which embodies novel features of construction whereby it can be readily applied to a wooden or metal beam at the ceiling or roof and will provide an effective means for supporting a block and tackle 20 in a shop or other place which is not equipped with a crane.

Further objects of the invention are to provide a device of this character which is comparatively simple and inexpensive in its 25 construction, which can be readily placed in position or removed therefrom, which can be applied to either a wooden or metal beam, and which provides an effective means for lifting and handling any heavy object.

With these and other objects in view, the invention consists in certain novel combinations and arrangements of the parts as will more fully appear as the description proceeds, the novel features thereof being 35 pointed out in the appended claims.

For a full understanding of the invention, reference is to be had to the following description and accompanying drawings, in which:—

40 Figure 1 is a side elevation of an overhead support for hoists constructed in accordance with the invention.

Fig. 2 is a detail view of the upper end of the support, showing the same as applied 45 to a steel beam.

Figure 3 is a detail perspective view of one of the jaws.

Fig. 4 is a detail perspective view of the upper end of one of the supporting links 50 and the slide which carries the same.

Fig. 5 is a detail view showing a slight modification of the invention.

Corresponding and like parts are referred to in the following description and indicated in all the views of the drawings by the same reference characters.

Referring to the drawings, which illustrate one embodiment of the invention, the numerals 1 designate a pair of levers which cross each other at intermediate points in 60 their length, being pivotally connected at their point of intersection by a suitable pivot pin 2. The lower ends of the levers curve downwardly and have extension handles 3 detachably applied thereto, while 65 the upper ends of the levers are extended upwardly and inwardly to provide hooks 1^a, and terminate in transversely extending jaws 4. These jaws project laterally in opposite directions from the levers so as to 70 obtain an extended bearing surface upon the beam, and the gripping faces of the jaws are preferably provided with teeth 5. When the support is applied to a wooden beam A, as indicated by Fig. 1, the jaws 75 4 engage opposite sides of the beam and the teeth 5 bite into the surface thereof. On the other hand, when the device is applied to a steel I-beam B the hooked ends 1^a of the levers fit around the lower flanges of 80 the beam, as indicated by Fig. 2.

The extension handles 3 are removable and provide a means for placing the device in position or removing it therefrom. It will be obvious, however, that these handles 85 can be detached after the support has been placed in position, thereby leaving a free clearance space on all sides of the block and tackle or other hoisting device, and enabling the hoist to be operated without interference by downwardly extending arms or handles at the sides thereof. In the present instance the lower ends of the levers 1 are shown as terminating in threaded stems 6 which are detachably engaged by sockets 7 95 at the upper ends of the extension handles 3, said sockets being adapted to be readily screwed upon or unscrewed from the threaded stems.

The curved lower ends of the levers 1 may 100 each be provided with a series of notches 8, and sleeves 9 are shown as slidably mounted upon the levers, said slides being formed with outwardly extending slotted ears 10 which receive suspending links 11. The 105 lower and inner ends of the suspending links engage a ring 12 from which a hoisting pulley 13 is suspended. When the links 11 are moved outwardly in the slotted ears 10 they are disengaged from the notches 8 and 110 the sleeves 9 can be moved longitudinally upon the lower ends of the levers, thereby

enabling the position of the sleeves to be adjusted. However, when the parts have been properly adjusted and the hoist is supporting a load, the links 11 are drawn to the 5 lower ends of the slotted ears 10 and held in engagement with the notches 8. The parts are thus locked in an adjusted position, and it will be obvious that the heavier the weight which is supported the more securely they 10 will be locked and the more tightly the overhead beam will be gripped by the jaws. The hoist is securely and conveniently supported from an overhead beam so that it can be used in the place of a crane where a shop is 15 not equipped with a crane, and the arrangement is such that the weight of the supported object acts upon the diverging lower ends of the levers 1 and tends to swing the jaws toward each other so that the heavier 20 the object the more firmly the jaws are held in position.

A slight modification is shown by Fig. 5, in which one of the levers 1 is provided with a swinging latch member L which is adapted 25 to engage a pin 20 on the other lever 1 to lock the levers against pulling apart when it is desired to maintain the support in the same position for a considerable length of time. The latch member L is pivotally connected at 21 to one of the levers 1, and provided at its swinging end with a series of notches 22, any selected one of these notches being adapted to be brought into engagement 30 with the pin 20 of the other lever 1 to lock the levers in position and prevent the jaws 4 from being swung apart and disengaged from the beam. A smooth edged plate 35 23 is pivoted at 24 to the latch L and when it is desired to render the latch L inoperative 40 this plate 23 is swung downwardly into alignment therewith so that the lower edge of the plate extends across the mouths of the notches 22 of the latch member and rests upon the pin 20, thereby preventing the pin 45 from entering and engaging one of the notches. This plate 23 is swung downwardly when the support is merely temporarily applied to the beam and it is not desired to lock it in position. The latch member L 50 drops by gravity into operative position, although it will be obvious that the notches 22 will be prevented from engaging and in-

terlocking with the pin 20 except when the plate 23 is swung upwardly into inoperative position. The overhead support may 55 thus be securely locked in position when it is desired to keep it in one place for any considerable length of time, and the locking device is automatic in its action except when the guard plate is swung downwardly to 60 render the latch plate inoperative.

Having thus described the invention, what I claim as new and desire to secure by Letters Patent, is:—

1. An overhead support for hoists including a pair of crossed and pivotally connected levers of which the lower ends diverge while the upper ends terminate in opposed jaws adapted to grip an overhead beam, slides mounted upon the diverging lower ends of 70 the levers, suspending links carried by the slides and mounted to have a limited movement relative thereto, locking means controlled by the said relative movement between the links and slides for holding the 75 slides in an adjusted position on the levers, and a hoist supported by the suspending links.

2. An overhead support for hoists including a pair of crossed and pivotally connected 80 levers, the lower ends of the levers diverging and being each provided with a series of notches, while the upper ends thereof terminate in opposed jaws which are adapted to engage an overhead beam, slides mounted upon the diverging lower ends of the levers and formed with slotted portions, suspending links carried by the slides and loosely received within the slotted portions thereof, 85 and a hoist supported by the links, the 90 weight of the hoist serving to hold the links in engagement with selected notches of the levers to lock the slides in adjusted positions, although by moving the links upwardly 95 within the slotted portions of the slides and disengaging the links from the notches the position of the slides can be adjusted.

In testimony whereof I have signed my name to this specification in the presence of two subscribing witnesses.

ADAM A. E. SNYDER.
